UNITED STATES PATENT OFFICE.

MAX DRUCKERMAN, OF BROOKLYN, NEW YORK.

AUTOMATIC STITCH-CONTROLLER.

1,089,751.

Specification of Letters Patent. Patented Mar. 10, 1914.

Application filed December 11, 1912. Serial No. 736,130.

To all whom it may concern:

Be it known that I, MAX DRUCKERMAN, a citizen of the United States, and a resident of Brooklyn, in the county of Kings and State of New York, have invented certain new and useful Improvements in Automatic Stitch-Controllers, of which the following is a specification, taken in connection with the accompanying drawings, which form a part 10 of the same.

My invention relates to sewing machines and more particularly to an automatic stitch controller for sewing machines having a vertically and laterally movable needle. This 15 general class of sewing machines, having a laterally and vertically movable needle, is old and applicant makes no claim to such a machine except when combined with his automatic stitch controller.

For purposes of illustration applicant has illustrated a sewing machine of this class, somewhat diagrammatically, simply that the 20 operation of his automatic stitch controller can be the more readily understood by those skilled in the art.

In the accompanying drawing showing 25 illustrative embodiments of my invention and in which the same reference numerals refer to similar parts in the several figures,— Figure 1 is a front elevation of my invention applied to a sewing machine having a laterally and vertically movable needle; Fig. 2 is a sectional and side elevation substantially on the broken line 2—2 of Fig. 1; Fig. 30 3 is a detail fragmentary plan view of the head of the sewing machine; Fig. 4 is a plan view of a fabric on which an embroidery seam, made of a plurality of uniform and symmetrical units are embroidered by means 35 of my automatic stitch controller; it being understood that the seam preferably conceals the fabric under it; Fig. 5 is a diagrammatic view of one unit of the embroidered seam, the distance between the threads 40 being purposely exaggerated for clearer illustration; Fig. 6 is a sectional view through a sewing machine showing a different arrangement of belts and pulleys from that shown in Figs. 1 and 2; and Fig. 7 is a 45 longitudinal vertical section through the clutch which I preferably employ, though it is to be understood, of course, that any form of clutch may be used.

In the illustrative embodiments of my invention shown in the drawings, 1 is a sewing 50 machine of any approved construction hav-

ing a head 2, a vertically and laterally movable needle 3 carried by a vertically and laterally movable needle bar 4 which, in turn, is carried by the link 5, Fig. 3 pivoted on the 55 presser foot bar 6. The needle bar is provided with a pitman 7 slidably connected to the needle bar rock-arm 8 which is pivoted on the head 2 at 9 and provided with a slot 10 for the reception of the slide 11 to which is connected a link 12, the other end of which 60 is connected to the lever 13 mounted on the rock shaft 14 (Figs. 1 and 3) which passes through the bearings 15 and 16 carried by the brackets 17 secured on the head 2 of the 65 machine in any suitable manner such as by the screws 18, 18. On the opposite end of the rock shaft 14 I mount an oppositely disposed lever 19 connected to a link 20 which is connected at its other end to a lever 21 70 pivoted at 22 to the head 2. The other end 75 23 of this lever 21 is provided with a split sleeve 24 to receive the controller rod 25. The adjustment between the controller rod 25 and the split sleeve 24, carried by the lever 21, is controlled by the screw or other connections 26, Fig. 2, so that the controller rod 25 can be adjusted in different positions within the split sleeve.

It is obvious that by pressing up on the 80 controller rod 25, against the action of the spring 27, that the lever 21 will be caused to rock on its pivot 22 which, in turn, will cause the link 20 to depress the lever 19, and this action will rock the rock shaft 14 and 85 cause the oppositely disposed lever 13 to draw up upon the link 12 and cause the slide 11 connected to it to approach nearer the pivot 9 of the needle bar rock-arm 8. It is well known in this class of machines that 90 this action will cause the slide 11, with its connected pitman 7 to rock in a smaller arc which will correspondingly decrease the lateral movement of the needle 3, causing it to make a shorter lateral stitch than it will 95 make when the slide is in the position shown in full lines in Fig. 1. The mechanism of the type of sewing machine just described is substantially old in the art and no claim is made to it *per se*.

My invention is in automatically and positively controlling the movement of the controller rod so as to automatically and positively form an embroidered seam of one or more units, preferably a plurality, in which 100 the lateral movement of the needle 3 will be caused to automatically make a predeter-

mined symmetrical unit having stitches of maximum and minimum length. I thus form an embroidery seam which will not only have its units symmetrically formed, but each thread in each unit will be automatically and positively formed in conformity with some predetermined form of embroidery, either identical with, or somewhat similar to, the fabric 28, Fig. 4, which is embellished with an embroidered seam 29 formed of a plurality of units 30, 30, each unit being composed of a certain predetermined number of maximum and minimum threads and a certain predetermined number 15 of intermediate threads of varying length, the whole being automatically, positively and symmetrically embroidered on the fabric.

For purposes of illustration I have shown 20 each unit of my embroidery seam 29 formed of sixteen needle threads which are shown diagrammatically in Fig. 5, the needle threads 31, 31 of minimum length and the maximum threads 32, 33, 34 and 35 being approximately the same length while the intermediate threads 36, 37, 38, 39 and 40 progressively increase in length from the minimum to the maximum threads. The needle threads as usual pass through the fabric 28 25 and form loops 41, 41 which, in my invention, are of different length and there co-operate with the shuttle or locking thread 42 which passes through the loops 41, 41 in the well known manner common to this class 30 of machines.

While I have shown my units 30, 30 formed of sixteen threads, it is, of course, to be understood that this number is simply by way of illustration and that the number of 40 threads in any unit may be increased or decreased as found convenient or expedient to make one or more symmetrical units.

My automatic controller is preferably driven by the same power as that which 45 drives the machine and will automatically and positively control and govern the lateral throw of the needle 3. Various means for accomplishing this result may be devised, the one shown being simply illustrative. Preferably I control the lateral 50 throw of the needle 3 by automatically controlling the movement of the controller rod 25.

By way of example I have shown a cradle 55 43 pivoted on the stand or bench 44, on which the head 2 of the machine rests. The cradle is preferably pivoted to plates 45 by means of the arbors 46. On this cradle I adjustably mount a pin 47 provided with a 60 head 48 which directly contacts with the end of the controller rod 25. The pin is preferably adjustably secured to the cradle 43 by means of the screw 49, Fig. 1. To this cradle I also adjustably secure a bent arm 50 65 having one end 51 adjustably secured in a

boss 52 carried by the cradle and co-operating with a set screw 53. The other end 54 of the bent arm 50 carries a wiper 55 which is preferably provided with a roller 56, to reduce the friction between it and the cam 70 57, mounted on the shaft 58. This shaft 58 is secured in bearings 59 carried by the uprights 60, 60. On this same shaft 58 I mount a pulley 61 which is temporarily secured to the cam 57 in any suitable manner 75 such as by the screws 62, 62. A belt 63 passes around the pulley 61 and around a smaller pulley 64 preferably carried by the driven pulley 65, the two being secured together in any suitable manner such as by the set screw 66, Fig. 7, the head of which is preferably sunk below the level of the groove 67 in the pulley 64. This driven pulley 65 is loosely mounted on the stub shaft 68 carried by the bracket 69, the stub 85 shaft being preferably secured immovably to the bracket by means of the set screw 70, Fig. 7. On this same stub shaft 68 I mount the conical drive pulley 71 and provide any suitable means which will permit the drive 90 pulley 71 to rotate loosely on the stub shaft 68 and yet have a limited lateral movement upon it so as to bring the clutch surface 72 on the drive pulley 71 in contact with the friction surface 73 on the pulley 65. One 95 manner of mounting this pulley is to provide the stub shaft 68 with a peripheral groove 74 and pass a pin 75 through the portion 76 of the drive pulley 71. This form of connection will permit free rotation 100 of the drive pulley on the stub shaft, the pin 75 rotating within its groove 74 and yet will permit lateral movement of the driving pulley 71 when it is desired to clutch the parts.

The clutch may be operated in any suitable manner. I have shown it operated by a bent arm 77 adapted to contact with the reduced end 78 of the friction pulley 71, the arm being mounted upon the rock shaft 79 (Figs. 1 and 2) which is mounted in the 110 sleeve 80 carried by the bracket 69. The other end of the rock shaft 79 is provided with an arm 81 upon which is mounted an offset portion 82 which lies beneath the offset or lug 83 carried by the bracket 69. Between the members 82 and 83 I mount a spring 84 which is compressed when the arm 77 is moved downward to contact with the reduced portion 78 to throw on the clutch. I preferably operate the arm 77 115 by a treadle 85 and adjustable connections 86 and 87.

The drive pulley 71 is normally operated by the drive belt 88. When it is desired to transmit power to the machine the treadle 125 85 is operated so as to depress the arm 77, cause it to engage with the reduced portion 78 to bring the friction surfaces 72 and 73 together and in that way transmit power to the driven pulley 65 which in turn trans- 120

mits power through the belt 89 to the sewing machine mechanism of the head through the pulley 90.

At the same time that the driven pulley 65 is transmitting power through the belt 89 to the pulley 90, the pulley 64 is transmitting power to pulley 61 through the belt 63 and causing the cam 57 to rotate with a certain predetermined speed, depending upon the relative size of the pulleys 64 and 61.

In the mechanism previously described, it is clear that the connections 55 and 50 will cause the cradle 43 to rock with a certain predetermined speed, dependent upon the speed of rotation of the cam 57 and this will automatically control the movement of the controller rod 25 and consequently control the lateral movement of the needle 3.

One revolution of the cam 57 and the pulley 61 makes one unit 30. Applicant has shown each unit formed of sixteen threads which is the particular unit formed by the particular gearing shown. It is obvious that as the number of stitches made by the machine is constant they can be automatically formed in units having a greater or a less number of stitches than sixteen by simply changing the relation of the controller gearing, as for example, by making the pulley 61 smaller, which will cause the number of stitches in the different units to decrease for the cam 57 would be caused to operate faster. Conversely, by enlarging the size of the pulley 61, each unit will contain a greater number of threads than sixteen for the cam 57 will rotate slower.

When either one unit has been formed, or a plurality of them as shown in Fig. 4, and it is desired to stop the machine for any purpose, it is merely necessary to operate the treadle 85 in a reverse direction which will release the clutch and at the same time will throw the brake 91, carried by the arm 81, into contact with the pulley 65, the spring 84 assisting this operation.

To insure the roller 56 contacting with the cam I preferably employ a spring 92 which has one end connected to the arm and the other to a fixed support (not shown, as this illustration would simply confuse the drawing). I also preferably employ a counter-weight 100 on the pulley 61 to balance the cam 57. I may in some cases have the belt 93 of the pulley 61 pass over the small pulley 94 shown in dotted lines in Fig. 6 which is mounted upon the needle bar shaft 95, instead of having the pulley 64 mounted upon the stub shaft 68 shown in Figs. 1, 2 and 7.

To make the embroidery units such as shown in Fig. 4, I employ the usual double presser feet 96, 96 mounted on the presser foot bar 6. My automatic stitch controller, however, will also make circular embroidery

seams in imitation of a leaf such as shown in my companion application executed contemporaneously with this application for an improved circular embroidery seam and filed at the same time being Serial No. 70 736,129. The automatic stitch controller will readily operate with the form of attachment shown in my Patent No. 1,051,315 for improvement in sewing machine.

Having thus described this invention in 75 connection with the illustrative embodiments thereof to the details of which I do not desire to be limited, what is claimed as new and what it is desired to secure by Letters Patent is set forth in the appended claims:

1. The combination in an embroidery sewing machine having a vertically and laterally movable needle-bar, of a depending slotted pivoted needle-bar rock arm, a slide mounted in the rock arm, connections between the slide and the needle-bar, a vertically extending link connected to the slide, a rock shaft, a lever mounted on the rock shaft and connected to the vertically extending link, an oppositely disposed lever mounted on the rock shaft, a depending controller rod, connections from the depending controller rod to the second lever, and automatic means independent of the depending controller rod and coöperating with it to 95 automatically govern the movement of the depending controller rod.

2. The combination in an embroidery sewing machine having a vertically and laterally movable needle-bar, of a depending 100 slotted pivoted needle-bar rock arm, a slide mounted in the rock arm, connections between the slide and the needle bar, a vertically extending link connected to the slide, a rock shaft above the plane of the sewing machine, a lever mounted on the end of the rock shaft adjacent to the rock arm, a link connecting the slide with the lever, an oppositely disposed lever mounted on the other end of the rock shaft, and connections from 110 that lever and on the opposite side of the machine from the rock arm connected with a depending controller rod, a depending controller rod and automatic means independent of the controller rod and coöperating with it to automatically govern the movement of the controller rod.

3. The combination in an embroidery sewing machine having a vertically and laterally movable needle-bar, of a depending 115 slotted pivoted needle-bar rock arm, a slide mounted in the rock arm, connections between the slide and the needle bar, a vertically extending link connected to the slide, a rock shaft above the plane of the sewing 120 machine, a lever mounted on the end of the rock shaft adjacent to the rock arm, a link connecting the slide with that lever, an oppositely disposed lever mounted on the other end of the rock shaft, and connections from 125 130

4
that lever and on the opposite side of the machine from the rock arm connected with a depending controller rod a depending controller rod, and automatic vertically operated means independent of the controller rod and coöperating with it to automatically lift the controller rod.

4. The combination in a sewing machine having a vertically and laterally movable needle, of a slotted pivoted needle bar rock arm, slide and connections to control the lateral throw of the needle, a controller rod, a support for the sewing machine, a cradle pivoted to the support and provided with a member to coöperate with the controller rod,

a stub shaft, a driven pulley mounted loosely upon the stub shaft, a drive pulley loosely mounted upon the stub shaft and adapted to have a relative longitudinal movement on the stub shaft, a pulley adapted to coöperate with the drive pulley, a cam carried by this latter pulley, a wiper carried by the cradle adapted to be operated by the cam, and means to move the drive pulley laterally to engage the driven pulley. 20
